LOUIS E. ROBINSON, OF COUNCIL BLUFFS, IOWA

PIPE CLEANING TOOL

Application filed May 14, 1931. Serial No. 537,384.

This invention relates to a tool for cleaning pipes, and more specifically soil pipes leading from water closets, these last named pipes having curved forms which may occasionally become obstructed.

The object of the invention is to provide a tool which will be convenient in use will be effective in removing obstructions from soil pipes, and will be of such simple construction that it will not be expensive in manufacture.

The invention consists of the new and useful construction, combination and arrangement of parts as described herein and claimed, and as illustrated in the accompanying drawings, it being understood that changes may be made in form, size, proportion of parts and minor details, said changes being within the scope of the invention as claimed.

In the drawings, Fig. 1 is a side view partly 20 in section showing the use of the tool applied to a soil pipe.

Fig. 2 is a broken away side view of the tool, with the hose pipe omitted. Fig. 3 is a similar view to that shown in Fig. 2, the hose pipe 25 being in position. Fig. 4 is a view in longitudinal section showing the terminal part of the tool.

Referring now to the drawings for a more particular description, the invention consists 30 of a coiled spring 5 which may be constructed of strong wire having a suitable degree of elasticity so that it will readily yield upon pressure and will assume its original spiral form when released from pressure. In outline it is of tapered form, said outline being 35 convergent toward its distal end. Numeral 6 indicates a handle for the tool.

Numeral 7 indicates a section of hose which is disposed in the spiral spring, the intake for the hose being indicated at 8 and 40 its discharge port being indicated at 9, said discharge port being a part of a valve-housing 10, the hinge valve controlling said discharge port being indicated at 11.

The hose is provided with a threaded collar 12 adapted to be mounted in the interiorly threaded end-portion 13 of the valve-housing. At 14 is indicated a detent-ring provided with a pair of opposed prongs 15. The 50 valve is provided with a buffer-plate 16 which

projects outwardly through the port 9 from the valve.

In Fig. 4 of the drawings the hose is shown in detached relation with the valve-housing, but it will be understood that the parts may be rotated for a mounting of the threaded collar 12 in the valve-housing.

It will be seen that since the prongs 15 project outwardly of the coiled spring 5 the valve-housing will not become detached 60 from the spring during use.

For operation, the spiral spring shown in Figs. 1 and 2 may be used without using the hose if desired, but in some instances the hose and its valve are of great advantage for removing obstructions, water under pressure being used and a connection being made with the intake 8 of the hose from any suitable source of supply, pressure of water in the 65 hose normally causing closure of the valve 70 11.

In operation, when the parts consist simply of the spiral spring shown in Figs. 1 and 2 for removing an obstruction, the handle 6 is used for rotating the tool, and since the 75 tool is elastic it may be moved through the curved parts of a pipe, and when the distal end of the tool engages an obstruction *x*, said obstruction will generally become caught between the coils, and the tool may then be 80 drawn outwardly for removal.

It will be seen that the valve-housing 10 may be adjusted longitudinally of the spiral spring 5 so that the buffer-member 16 may be disposed closely adjacent to the terminal 85 hook 17 of the spiral spring 5, or in advance of said hook.

The valve may be readily attached or detached from the hose. After the ring 14 has 90 been placed a suitable distance from the hook 17 between a pair of adjacently disposed coils of the spring the valve-housing is inserted and, by rotating these parts, the valve-housing will become threaded in the detent-ring.

Since the hose is flexible the tool may be rotated in the manner already mentioned, and an obstruction may be engaged by the hook 17 for removal. In some instances how- 100

ever, the obstruction may be of such consistency that the spiral spring will not move forwardly in the pipe and in such instances the obstruction may be softened by use of water from the hose, and in operation, when the tool moves forwardly the detent member or plate 16 will be pressed rearwardly in a manner to move the valve to open position to permit water to move to advantage against the obstruction to cause disintegration in a degree to permit removal.

It will be appreciated that the tool consists of few parts to permit convenient and economical production, and on account of its novel features of construction it will be effective in removing obstructions from pipes having the curved forms mentioned.

I claim as my invention,—

- 20 1. A pipe cleaning tool comprising an elongated coiled spring provided with a handle at one of its ends and having a tapered form in outline from its handle toward its opposite end.
- 25 2. A pipe cleaning tool comprising an elongated wire coil provided with a handle at one of its ends, a flexible hose disposed in the coil and having a valve arranged to permit a discharge of liquid at that end of the wire coil opposite to the handle.
- 30 3. A pipe cleaning tool comprising a wire bent to provide an elongated coiled part and a handle at one end of the coiled part, a valve-housing having a discharge port and disposed in that part of said coiled part opposite to said handle, a detent-ring on the valve-housing having projections extending outwardly of said coiled part, a valve in said housing having a buffer-member extending outwardly of said discharge port, and 40 a hose disposed in said coiled part adapted to communicate with the valve-housing for conducting a liquid thereto.

In testimony whereof, I affix my signature.

LOUIS E. ROBINSON.
